United States Patent Office

MERWIN FOWLER, OF WOLCOTTVILLE, CONNECTICUT.

Letters Patent No. 62,832, dated March 12, 1867.

IMPROVEMENT IN BUCKLES.

The Schedule referred to in these Letters Patent and making part of the same.

TO ALL WHOM IT MAY CONCERN:

Be it known that I, MERWIN FOWLER, of Wolcottville, in the county of Litchfield, and State of Connecticut, have invented, made, and applied to use a certain new and useful Improvement in Buckles; and I do hereby declare the following to be a full, clear, and exact description of the said invention, reference being had to the annexed drawing, making part of this specification, wherein—

Figure 1 is a perspective view of said buckle.

Figure 2 is a plan; and

Figure 3 is a section of said buckle in a slightly modified form.

Similar marks of reference denote the same parts.

Buckles have heretofore been made without penetrating teeth or tongues, the strap being clamped between two pieces of metal. The nature of my said invention consists in a buckle formed with a wire bow, that has a double or return bend in the sides to form the axis for a loop that is made with eyes at its ends, passing around the wire of the buckle bow at this point, so that the buckle has an attaching bow at one end, and at the other end the strap is held by passing around the clamping bow between it on the main bow. My buckle is strong, easily made, and especially adapted to the bands of skeleton-skirts, vests, and other articles of wearing apparel.

In the drawing, *a* represents the main bow of the buckle, that is formed with a double bend, *x*, in the sides, as in fig. 1, to form an attaching loop, *b*. *c* is the clamping bow, made with eyes, *e*, at its ends, passing around the wire of the bow *a*, at the point where the double bend *x* is formed, so that the parts turn on each other at this point. The strap is passed through in the direction shown in fig. 3, and is held by being clamped between the parts of the buckle *a* and *c*.

What I claim, and desire to secure by Letters Patent, is—

A buckle formed of the wire bow *a*, attaching bow *b*, and clamping bow *c*, formed with eyes *e*, passing around the wire of the bow *a*, at the return bends *x*, as and for the purposes specified.

In witness whereof I have hereunto set my signature this 22d day of October, A. D. 1866.

MERWIN FOWLER.
